[57] CLAIM

The ornamental design for a faucet-attached suction pump for a dental plaque cleaner, as shown and described.

DESCRIPTION

FIG. 1 is a bottom and rear perspective view of a faucet-attached suction pump for a dental plaque cleaner showing my new design;

FIG. 2 is a right side elevational view thereof, the left side being a mirror image of that shown;

FIG. 3 is a front elevational view thereof;

FIG. 4 is a rear elevational view thereof;

FIG. 5 is a top plan view thereof; and

FIG. 6 is a bottom plan view thereof.
